United States Patent Office

Des. 184,586
Patented Mar. 10, 1959

184,586

PLATE OR SIMILAR ARTICLE

Gerald S. Stone, Scarsdale, N. Y., assignor to Johnson Bros. (Hanley) Limited, Stoke on Trent, England, a company of Great Britain

Application March 31, 1958, Serial No. 50,254

Term of patent 14 years

(Cl. D44—15)

In the drawing a top plan view of a plate or similar article of conventional configuration illustrates my new design.

I claim:

The ornamental design for plate or similar article, substantially as shown and described.
